WIRE-LACING APPARATUS

Oscar F. Arthur, Belle Vernon, Pa.

Application October 13, 1942, Serial No. 461,872

8 Claims. (Cl. 140—3)

My invention relates to wire lacing apparatus and more particularly to a machine for use in forming wire mesh panels disclosed in my application Serial No. 437,989, filed April 7, 1942 (now Patent 2,315,180, issued March 30, 1943), although the apparatus can be used in performing lacing operations for other purposes.

One object of my invention is to provide apparatus of such form that a connection can readily be made between the wires of a mesh and a plate or marginal bar.

Another object of my invention is to provide an improved means for properly spacing the protruding wires of a mesh structure and aligning them relative to one another and to a member to which they are to be connected.

In the accompanying drawings, Figure 1 is a perspective view of the machine; Fig. 2 is a perspective view showing in disassembled relation the parts which are to be joined together; Fig. 3 is a plan view of a portion of a completed mesh panel structure; Fig. 4 is an end view of the machine of Fig. 1, partly in section; Fig. 5 is a plan view thereof, and Fig. 6 is a front view of the machine.

Referring first to Figs. 2 and 3, the parts to be assembled comprise a mesh 7, only one end of which is shown; a perforated plate 8 and a lacing rod or wire 9. The mesh sheet has projecting strand portions 10 with bends 11 formed therein in any suitable or convenient manner, as by pressing dies or rolling, it being understood that at the opposite edge of the sheet the strands can project in a similar manner for connection to another perforated plate. The machine positions or aligns the projecting portions 10 in properly spaced relation, so that the bends 11 will readily enter the slots 12 in the plate 8, and be projected therethrough to permit the insertion of the lacing wire 9.

The machine has a framework that comprises horizontally-extending frame members 14 that will be supported upon a suitable base, and uprights 15 and a top cross bar 16. Vertical guides or slideways 17 are secured in the framework and have riveted thereto strips or bars 18 that serve as guideways for upright arms 19 of a cross-head 20, so that such cross-head can have vertical movements in the framework.

A cylinder 22 is rigidly secured in the framework and contains a piston 23 whose rod 24 is connected to the cross-head 20, so that as the piston moves down, the cross-head will be moved down against the tension of springs 25 that connect the ends of the cross-head with the top bar

16, the springs 25 serving to raise the cross-head when fluid is exhausted from the upper side of the piston 23. A breather opening 26 is provided in the lower part of the cylinder to permit unrestricted operation of the piston. A drain pipe 27 is provided for receiving oil that leaks past the piston and for conducting it to a point at which it can be collected, where oil is used as the motive fluid.

Fluid pressure is admitted from a supply line 29, past a valve 30 and to a pipe 31 leading into the upper end of the cylinder 22, to force the piston down. At the completion of such a movement, the valve handle 32 is turned to shut off flow from the pressure line 29 and effect connection between the pipe 31 and an exhaust pipe 33, so that the springs 25 will raise the piston and the cross-head.

The cross-head carries a pair of angular holding members 34 and forwardly thereof it pivotally supports a pair of gripping members or fingers 35. The fingers are yieldably urged toward the members 34 by springs 36 that are contained within tubular casings 37, so that they will grip the edges of the bar 8 to hold it in place beneath the cross-head, as indicated in Fig. 4. The bar will be inserted by pressing its forward edge against the rear faces of the fingers 35 and pushing said fingers outwardly far enough to let the rear edge of the bar enter the angular holding members 34, the bar being thereby frictionally held. A series of bosses 38 are secured to the underside of the cross-head 20 and have grooves 39 formed therein (Fig. 4) to receive the bends 11 of the strands. These bosses are so arranged that each curved recess 39 will lie directly above one of the slots 12 in the plate 8, so that the recesses will be in position to receive the bends 11 when they are inserted through the slots. The forward and rear edges of these bosses will be engaged by the unperforated edge portions of the plate.

An anvil bar 41 is supported on the frame members 14 and carries a series of aligning fingers 42 that are beveled at their upper ends so as to facilitate the placing of the projecting portions 10 of the strands between the fingers by vertically downward movement of the mesh upon the anvil. The mesh can be placed on the anvil manually when the cross-head 20 is in raised position. As shown in Fig. 6, there will be one wire in each space between the fingers, except at the edges of the fabric where two strands are found.

The anvil has a pair of brackets 43 which serve as spring seats and guides for bolts or rods 44 that extend through springs 45 and at their upper

ends support a bar 46 which carries a series of guide fingers 47. The springs yieldably support the bar 46 and its fingers in raised position, but a downward thrust upon the bar will compress the springs and move the rods 44 downwardly. The heads of these rods limit the upward movement of the bar 46. In the bar 8 the web elements 49 that constitute unperforated areas between the slots 12 overlie the guide fingers 47, so that when the cross-head 20 is lowered, these elements 49 will push the guide fingers and the cross-bar 46 downwardly against the pressure of the springs 45, until the upper ends of the fingers are approximately flush with the top surface of the anvil 41.

In the operation of the apparatus, the bar 8 and the mesh 7 are preformed previous to assembly. The bar 8 is inserted between the gripping elements 34-35 as shown in Fig. 4, at the full-line position of the holders 34-35. The mesh 7 is then brought into such position that its extended portions 10 will be disposed between the aligning fingers 42 and the bends 11 between the guide fingers 47, as indicated in Figs. 4 and 6. The extended portions 10 usually are not in perfect alignment after crimping, and the fingers 42 and 47 will serve to align and space them properly, including the alignment of the bends 11 with the slots 12. The cross-head 20 is then moved downwardly by the piston, to its dotted line position (Fig. 4). During such movement the slots 12 will receive the bends 11 and at the same time the fingers 47 will be pushed to retracted position as above explained, by the web elements 49 on the plate 8. The bends are thus maintained in their previously aligned positions, since the guide fingers 47 do not pass out of engagement with the sides thereof until the bends are entering the slots 12 of the plate. The side walls of these slots therefore retain the bends in their upright positions for the reception of the lacing wire 9. While the parts occupy these positions, with the bends lying in the curved recesses 39 on the cross-head, the lacing wire 9 will be slid into place between the upper side of the plate 8 and the bends 11, thus connecting the mesh to the plate. Thereupon pressure will be exhausted from the upper side of the piston 23, allowing the springs 25 to raise the anvil. During this raising movement, the holders 34-35 will be stripped from engagement with the edges of the plate 8. The mesh and the plate can then be lifted clear of the fingers 42 and 47.

The mesh at its other end can be connected in a similar manner to another plate 8, or a machine can be provided for connecting plates to each end of the mesh simultaneously.

I claim as my invention:

1. Apparatus for making a laced connection between an apertured plate and a wire mesh that has a row of laterally-spaced bends formed therein for insertion into the plate apertures, comprising a surface for supporting the mesh adjacent to the opened sides of said bends, guide fingers spaced apart at said surface, for the reception of said bends between them, and means for yieldably holding the fingers in said position, the said means being so arranged that when the plate is moved toward the said surface, with its apertures in alignment with the said bends, the unapertured areas of the plate will push the fingers to retracted position, and the bends will be moved through the plate apertures a sufficient distance to accommodate a lacing wire between said bends and the adjacent side of the plate.

2. Apparatus for making a laced connection between an apertured plate and a wire mesh that has a row of laterally-aligned bends formed therein for insertion into the plate apertures, comprising means for supporting said bends in position to pass through the plate apertures, when the plate is moved toward the mesh, whereby a lacing wire can be inserted between the bends and the adjacent side of the plate, the 10 said means including guide fingers for directing misaligned bends into parallel planes when the mesh is brought into engagement therewith, and means for moving the guide fingers to retracted positions when the plate is brought into such position that its apertures will receive the said bends.

3. Apparatus for making a laced connection between an apertured plate and a wire mesh that has projecting strand portions with bends formed therein for insertion into said apertures, comprising a row of laterally-spaced aligning fingers spaced apart for the reception between them of the projecting portions of the strands, a row of laterally-spaced guide fingers each normally located opposite to one of the aligning fingers, means for yieldably holding the guide fingers in their said opposite positions and positioned to receive the said bends, a holder for the plate, and curved recesses in the holder, which are positioned to receive the said bends when they are pushed through the slots in the plate, those plate areas between the slots serving to push the guide fingers to retracted position when the holder is moved toward the ends of the guide fingers, whereby such fingers will be pushed clear of the bends.

4. Apparatus for making a laced connection between an apertured plate and a wire mesh that has projecting strand portions with bends formed therein for insertion into said apertures, comprising a row of laterally-spaced guide fingers, means for yieldably holding the guide fingers in a projected position and positioned to receive the said bends, a holder for the plate, and curved recesses in the holder, which are positioned to receive the said bends when they are pushed through the slots in the plate, those plate areas between the slots serving to push the guide fingers to retracted position when the holder is moved toward the ends of the guide fingers, whereby such fingers will be pushed clear of the bends.

5. Apparatus for making a laced connection between an apertured plate and a wire mesh that has projecting strand portions with bends formed therein for insertion into said apertures, comprising an anvil surface, a row of laterally-spaced guide fingers projecting upwardly from said surface, means for yieldably holding the fingers in their upwardly projected positions to receive the said bends between them, and a cross-head for releasably supporting the plate in such position that its apertures are directly above the said fingers, the cross-head being movable toward the said anvil to push the fingers to retracted position and effect entry of the said bends through the apertures.

6. Apparatus for making a laced connection between an apertured plate and a wire mesh that has projecting strand portions with bends formed therein for insertion into said apertures, comprising an anvil surface, a row of laterally-spaced guide fingers projecting upwardly from said surface, means for yieldably holding the fingers in their upwardly projected positions to receive the said bends between them, and a cross-

head for releasably supporting the plate in such position that its apertures are directly above the said fingers, the cross-head being movable toward the said anvil to push the fingers to retracted position and effect entry of the said bends through the apertures, and the cross-head having recessed elements thereunder, curved to a contour approximating the shape of the bends.

7. Apparatus for making a laced connection between an apertured plate and a wire mesh that has a row of laterally-spaced bends formed therein for insertion into the plate apertures, comprising a surface for supporting the mesh adjacent to the open sides of said bends, a member having means thereon for releasably supporting the plate, means for moving the member perpendicularly to the plane of the mesh and to a position against the same where the said bends project through the plate apertures, the plate

being removable from the said member when the plate is held in position on the mesh.

8. Apparatus for making a laced connection between an apertured plate and a wire mesh that has a row of laterally-spaced bends formed therein for insertion into the plate apertures, comprising a surface for supporting the mesh adjacent to the open sides of said bends, a member having means thereon for releasably supporting the plate, means for moving the member perpendicularly to the plane of the mesh and to a position against the same where the said bends project through the plate apertures, the releasable connection between the plate and its supporting member being automatically broken upon withdrawal movement of said member when the plate is held in position on the mesh.
